(57) **CLAIM**

The ornamental design of a barbecue grill handle, as shown and described.

DESCRIPTION

FIG. 1 is a top front perspective view of a barbecue grill handle showing my new design, the portions shown in broken lines are for environmental purposes only and form no part of the claimed design;

FIG. 2 is a top plan view thereof;

FIG. 3 is a front view thereof;

FIG. 4 is a left side view thereof, the opposite side being a mirror image;

FIG. 5 is a rear view thereof; and,

FIG. 6 is a bottom view thereof.
